Primary Examiner — Abraham Bahta

(57) **CLAIM**

I claim the ornamental design for a silicone bag device, as shown and described.

DESCRIPTION

FIG. 1 is a perspective view of a silicone bag device showing the new design; and

FIG. 2 is a left side view;

FIG. 3 is a front view;

FIG. 4 is a right side view;

FIG. 5 is a rear view;

FIG. 6 is a bottom view; and,

FIG. 7 is a top view.
